UNITED STATES PATENT OFFICE.

ELLSWORTH A. HAWTHORNE, OF BRIDGEPORT, CONNECTICUT.

LAMP AND NUMBER-PLATE BRACKET.

1,207,292.

Specification of Letters Patent.

Patented Dec. 5, 1916.

Application filed August 2, 1913. Serial No. 782,568.

To all whom it may concern:

Be it known that I, ELLSWORTH A. HAWTHORNE, a citizen of the United States, and a resident of Bridgeport, county of Fairfield, and State of Connecticut, have invented an Improvement in Lamp and Number-Plate Brackets, of which the following description, in connection with the accompanying drawings, is a specification, like 10 characters on the drawings representing like parts.

This invention relates to lamp and license number-plate brackets for motor vehicles, such for example as motor cycles, and will 15 be best understood by reference to the following specification, when taken in connection with the accompanying drawings of two specific embodiments thereof, while its scope will be more particularly pointed out in the 20 appended claims.

In the drawings: Figure 1 is a rear elevation of one form of lamp and license number-plate bracket, embodying my invention, the lamp, number-plate and mud-guard of 25 the motor cycle being indicated in dotted lines; Fig. 2 is a side elevation of the same, also showing the lamp, number-plate and mud-guard in dotted lines; Fig. 3 is a rear elevation of another form of bracket embodying my invention; and Fig. 4 is a side 30 elevation of the same, showing a lamp battery and mud-guard in dotted lines.

Referring to the drawings, and to the 35 embodiments of my invention which I have selected for illustration, I have there shown two lamp and number-plate brackets similar to each other in most respects, but differing in other respects. The features common to both brackets will first be described, using 40 the same reference characters as applied to both, and the features in which the brackets differ will be afterward separately described.

In both embodiments illustrated, the numeral 5 designates generally a strap-like 45 member having two sides, or arms, 6 and 7, disposed preferably substantially at right angles to each other, and forming a generally L-shaped structure, the arm 6 having a terminal portion 8 disposed at an angle to

the contiguous part of the arm, and provided with a perforation 9 to receive a screw, by means of which it may be secured to the mud-guard, the latter being indicated in dotted lines in Figs. 1, 2 and 4.

The member 5 is provided with a perforation 10, preferably located adjacent the apex of the angle formed by the arms 6 and 7. Surmounting the member 5 is a second member 11, also formed of a strip of metal, and preferably having a generally U-shaped 55 form, being provided with two arms 12 and 13, the former having a terminal portion constituting a tongue 14, offset substantially parallel to the arm 12, and extending through the perforation 10 onto the opposite side of the arm 7. The other arm 13 of this member is provided with a terminal portion 15, bent substantially at right angles 60 thereto, and parallel to the arm 6. This terminal portion is provided with a perforation 16, registering with a similar perforation 17 formed in the arm 6, and through 65 both these perforations a clamping bolt 18 extends, and is provided with a wing-nut 19, which may be located above or below, according as circumstances may require.

When the bracket is used to support a lamp having as its source of supply a battery, the casing of the latter, indicated in dotted lines in Fig. 4, will be inclosed in the 70 space bounded by the arms 12 and 13 and the arm 6, and will be firmly held in place, yet may be quickly and conveniently removed by simply withdrawing the bolt 18 and swinging the member 11 about the offset 75 portion of its tongue 14 as a fulcrum, until the tongue arrives in a position where it can be withdrawn from its perforation 10. The lamp, which is indicated in dotted lines in 80 Figs. 1, 2 and 4, at the front of the arm 12, 85 is intended to be secured to the latter in any appropriate manner, as by means of rivets or screws, the arm for this purpose being 90 provided with perforations 20 and 21.

When the lamp is to be supplied with current from a generator or battery located at a 95 point distant from the bracket, the lamp may be provided with a rearward extension

or connection, as indicated in dotted lines in Fig. 2, and to support this extension, the arms 12 and 13 are herein provided respectively with apertures 22 and 23, placed in line with each other.

The arm 7 is intended to support a license number-plate beneath the lamp, where the latter will shed a part of its rays of light upon the face of the number-plate to illuminate the latter, and for this purpose, the arm is herein provided with perforations 24 and 25, to receive the usual screws, by means of which the number-plate is attached to the bracket. In some cases, it is desirable to place the bracket as low as possible upon the mud-guard, while in other cases, it may be placed at a considerable distance from the lower terminal portion of the mud-guard.

In Figs. 1 and 2, I have shown the bracket as constructed when intended to be placed at a point very low down upon the mud-guard, and in this form, the arm 7 is provided with a terminal portion 26, bent forwardly and then upwardly, so as to extend 20 in the same general direction as the terminal portion 8 already referred to. In order to provide for the attachment of the terminal portion 26 to the mud-guard, yet without interfering with the usual spring, which in most motor cycles is disposed 25 within the central portion of the mud-guard, the terminal portion is herein provided with a pair of ears 27, provided respectively with perforations 28 to receive screws or 30 bolts for the attachment of the ears to the mud-guard. These ears may be formed and herein are formed as a part of a separate plate 29 overlying the terminal portion 26, and bent to conform to the transverse contour 35 of the mud-guard, the central portion of the plate being secured to the terminal portion 26 by any appropriate means, as for example rivets 30.

In the form shown in Figs. 3 and 4, the arm 7 is provided with a depending terminal portion 31, bent at a slight angle to the arm, and herein provided with perforations 32 and 33, to receive screws for the attachment of the terminal portion to the 45 mud-guard.

It will be observed that, in both forms of the invention, the terminal portions of both arms of the bracket are shaped to conform substantially to an arc of a circle struck 50 from a center located within the angle included by the two arms; that is to say, they are so formed as to fit the curve of the mud-guard of the motor cycle. In the form shown in Figs. 1 and 2, the terminal portion 26 extends toward the terminal portion 8, and in this form as before stated, owing 55 to this feature, the bracket can be placed at a point well down on the mud-guard, while in the form shown in Figs. 3 and 4,

the terminal portion 31 extends in the opposite direction, to adapt it to other requirements where the bracket is not required to be placed near the bottom of the mud-guard, or where the latter is extended to a point sufficiently low to receive a terminal portion 65 of a character shown in Figs. 3 and 4.

While I have herein shown and described two specific embodiments of my invention for illustrative purposes, and have disclosed and discussed in detail the construction and arrangement incidental to two specific applications thereof, it is to be understood that the invention is limited neither to the mere details or relative arrangement of parts, nor to its specific embodiments herein shown, 70 but that extensive deviations from the illustrated forms or embodiments of the invention may be made, without departing from the principles thereof, as set forth in the appended claims.

Having thus described my invention, what I claim and desire by Letters Patent to procure is:-

1. A bracket of the class described comprising, in combination, two parts one of 90 which is generally L-shaped in form and is provided adjacent its apex with a perforation, and the other of which has two terminal portions one of which is in the form of a tongue having an offset extending 95 through said perforation, and means to secure the remaining terminal portion to the other of said parts.

2. A bracket of the class described comprising, in combination, two parts one of 100 which is generally L-shaped in form and is provided with a perforation, and the other of which is generally U-shaped in form and has two arms one having a tongue offset substantially parallel to its arm and extending through said perforation, and means to secure the other arm to the other 105 of said parts.

3. A bracket of the class described comprising, in combination, two parts one of 110 which is provided with a perforation, and the other of which is generally U-shaped in form and has two arms one having a tongue offset substantially parallel to its arm and extending through said perforation, and a 115 bolt passing through the other arm and the other of said parts.

4. A bracket of the class described comprising, in combination, two parts one of 120 which is provided with a perforation, and the other of which is generally U-shaped in form and has two perforated arms one having a tongue offset substantially parallel to its arm and extending through said perforation, and a bolt passing through the other 125 arm and the other of said parts.

5. A bracket of the class described comprising, in combination, two parts one of

which is generally L-shaped in form and has two arms provided with perforated terminal portions and is provided with a perforation adjacent the juncture of said arms, 5 and the other of which is generally U-shaped in form and has two arms one of which is provided with a tongue offset and extending through said perforation, the remaining arm of each of said parts being provided 10 with a perforation, one registering with the

other, and a bolt passing through said registering perforations.

In testimony whereof, I have signed my name to this specification, in the presence of two subscribing witnesses.

ELLSWORTH A. HAWTHORNE.
